UNITED STATES PATENT OFFICE.

CHARLES GOLDEN FULKS, OF HUNTINGTON, WEST VIRGINIA.

BLUE-FLAME BURNER.

Application filed September 5, 1923. Serial No. 661,060.

The present invention relates to a blue flame gas burner which is primarily intended for use in connection with incubators.

It is very essential to maintain the heat in an incubator constant, and one object of the invention is to so construct the burner that when the heat in the incubator rises above a certain predetermined amount, the burner will be cut off until the heat is normal and relight itself when the heat in the incubator becomes lower than a certain predetermined amount.

In the accompanying drawings, one embodiment of the invention is illustrated, and—

Figure 1 is a vertical section of the burner, and

Figure 2 is a transverse section along line 3—3 of Figure 1.

The burner consists of a solid base 12 recessed to form a passage 12' and carrying an upright pipe 13 connected with said passage. At the upper end of the pipe 13 is attached a sleeve 16 in which a valve plug 17 is mounted to rotate and formed in the plug is a transverse port 18 for passing the gas from the pipe 13 upwardly in the sleeve 16. One end of this valve plug 17 carries a lever 19 to which is positively connected a wire 20 for operating the valve from any convenient point.

At the upper end of the sleeve 16 is mounted a mixing tube 22 which is connected to a burner head 23. The mixing tube has air ports 24 and is provided internally with a portion 24' defining a reduced axial gas passage 24'' leading from the lower end of the tube and terminating at the level of the lower limit of the ports 24. The passage is tapered from its lower end toward its upper end and will thus discharge a jet of gas at increased pressure axially into the lower end portion of the tube between the lower ends of the ports 24 so that a proportionately large supply of fresh air will be drawn in through said ports to mix with the gas. The head 23 is solid and is recessed at its upper end to form a chamber 25 connected with the tube 22 by a reduced axial passage 25'. Thus, the mixture of air and gas emerging from the mixing tube will be initially heated by the head as the mixture flows through the passage 25' to the chamber 25 where the mixture will then be further heated before the

final combustion thereof. Leading from the chamber 25 are radial passages 26 opening through the periphery of the burner head under a top plate 27 which extends slightly beyond the discharge ends of said passages so as to provide a flame spreader and throw the flame outwardly from the burner.

A pilot burner 28 is provided at the upper end of a small tube 29 which is carried at the lower end of the sleeve 16. The pilot burner opens to one side of the burner head 23 and communicates with the passage of the sleeve 16 below the valve plug 17, so that the pilot burner 28 will always be supplied with gas as long as the valve 15 remains open, whether the valve plug 17 be open or closed. Consequently, if the lever 19 on the valve plug 17 is turned to obstruct the passage of the gas through the sleeve, the pilot burner 28 will remain lighted while the main burner will be extinguished. Accordingly, when the lever 19 is again turned to admit gas to the main burner, said main burner will be immediately relighted by the pilot burner 28. At 30 is shown a set screw for adjusting the inlet opening of the pilot tube 29 to control the amount of gas supply to the pilot burner.

On the short pipe 22 is mounted a cone-shaped hood 31 extending upwardly above the burner head 23 and connecting with a cylindrical flue 32 for carrying away the burnt gases. This hood is secured on the short pipe 22 by means of a clamping screw 35. The base of the hood 31 has a central opening from which depends a collar 31^b, and openings 31^a grouped about the central opening. The mixing tube 22 passes through the collar 31^b and the central opening of the base and is secured thereto by a clamp screw 35 threaded into a side of the collar 31^b. Around the flue 32 is mounted a drum 33 closed on all sides but having a branch 34 for connecting the drum with the interior of an incubator.

Having thus described the invention, what is claimed as new is:

A burner of the character specified comprising a base in which is formed a passage to receive gas from a suitable source of supply, an upright pipe attached to the base and in communication with the passage thereof, a sleeve at the upper end of the pipe, a valve in the sleeve, a mixing tube con-

ected to the sleeve and having air inlet ports in its sides, a burner at the upper end of the mixing tube, a hood inclosing the burner and having a depending collar ¹⁰ through which passes the mixing tube and having air inlets in its base, means carried by said collar to secure the hood on the mix-

ing tube and a tube connected with the said sleeve below the valve thereof and passing through an air inlet in the base of the hood and terminating adjacent the burner.

In testimony whereof I affix my signature.

CHARLES GOLDEN FULKS. [I.S.]
